S. H. SHAW

BUMPER

Filed Nov. 12. 1923

2 Sheets-Sheet 2

UNITED STATES PATENT OFFICE.

SAMUEL H. SHAW, OF NEW YORK, N. Y.

BUMPER.

Application filed November 12, 1923. Serial No. 674,115.

To all whom it may concern:

Be it known that I, SAMUEL H. SHAW, a citizen of the United States, residing at New York city, in the county of New York and State of New York, have invented certain new and useful Improvements in Bumpers, of which the following is a full, clear, and exact description.

This invention relates to bumpers for attachment to the front or rear end of a vehicle for the purpose of absorbing shocks or impacts due to collision of the vehicle with another vehicle, or with an obstruction, and thus lessen or avoid injury to the colliding bodies. In the absence of a standard or customary height of bumpers above the roadway it is desirable that the bumpers be capable of engaging with bumpers at different heights on other vehicles with which the carrying vehicle may collide.

An object of the invention is to provide an improved bumper which will have sufficient vertical dimensions or will present sufficient impact surface to be engageable with bumpers at different heights upon other vehicles with which the carrying vehicle may collide; which may be formed of a relatively small amount of stock material, preferably largely from flat strips of metal of uniform width; which will retain, as far as economically possible, all of the advantage relative to the capacity of a one-piece impact plate; which is resilient and possesses maximum effectiveness in resisting the stresses of collision; which is exceptionally simple in construction and manufacture, durable, attractive in appearance, and relatively inexpensive and light in weight. Other objects and advantages will be apparent from the following description of several embodiments of the invention.

The details of the invention will hereinafter appear, and the novel features will be particularly pointed out in the claims.

In the accompanying drawings:

Fig. 1 is a plan of a bumper constructed in accordance with the invention;

Fig. 2 is a front elevation of the same;

Fig. 3 is an end elevation of the same;

Fig. 4 is a sectional elevation of the same, taken substantially along the line 4—4 of Figure 2;

Fig. 5 is a plan of another embodiment of the invention;

Fig. 6 is a front elevation of the same;

Fig. 7 is a front elevation of a portion of

the bumper shown in Figures 5 and 6, on a slightly larger scale, and having a portion broken away to show details;

Fig. 8 is a sectional elevation of the same taken substantially along the line 8—8 of Figure 6;

Fig. 9 is a plan of a portion of a bumper illustrating a further embodiment of the invention;

Fig. 10 is a front elevation of the same; and

Fig. 11 is a section of the same taken substantially along the line 11—11 of Figure 10.

Referring particularly to Figures 1 to 4, a pair of U-shaped impact units 1 and 2 are arranged to extend in opposite directions and transversely of the vehicle, with the free end of the arms of each unit overrunning with that of the other unit, and with the arms of each unit superposed vertically relatively to one another. The overrunning arms may be secured together in any suitable manner, such as by clamps 3 which embrace the overrunning arms, the clamping action being varied by a suitable clamping bolt or screw 4. The base or cross arm portion 5 of the U of each unit is curved backwardly upon itself in spaced relation to the major portion of the unit.

A bar or member 6 of spring metal is secured, at a point intermediate of its length, by a bolt 7 to the base portion 5 of each unit, the strip 6 extending along the inner face of the curved back portion of each unit and thence for a short distance along the inner face of the major portion of the unit, the ends of each strip being curved in a direction transversely of the units for attachment to the side bars 8 of a vehicle frame. One of the ends 9 of each strip 6, which extends directly from the base portion of the unit, passes along one face of a suitable bracket member 10 which is secured in any suitable manner to the side bar 8 of the chassis frame, the end 9 being, for example, attached to the bracket by suitable bolts 11. The end of each strip 6, which extends along the inner face of the unit, is embraced by one of the clamps 3 and passes beyond the adjacent side bar 8 of the chassis frame, curves to extend along the side bar 8 and then the extreme end 12 extends in the reverse direction along the side bar of the frame for attachment to the

spring bolt 13 in the end of the side bar. The bracket member 10 may be secured to

the side bar 8 in any suitable manner, such as by the spring bolt and also by a hook bolt 13^a passing through the bracket member and having a hooked end 14 in hooked engagement with the opposite face of the side bar 8. A bolt 15 passes through the outer end of the bracket member 10 and has an angular end 16 surrounding the spring bolt 13 at the opposite face of the side bar and 10 clamping the end 12 of the strip 6 against the side bar 8.

The units may be stamped in U-shape from suitable sheet metal stock and the base portions then bent backwardly upon themselves, or the units may be formed of a single uniform strip of flat metal bar which is bent within its plane into substantially U-shape to provide the U-shape member, and the base portion then subsequently bent 20 backwardly upon itself. Both units may be identical in construction and may have arms of equal or unequal length. Each unit will be supported with its arms vertically above one another so as to present sufficient impact surface or vertical dimensions to engage with bumpers on colliding vehicles which may be located both above and below the level generally protected by bumpers having straight impact members.

30 When a bumper constructed in this manner is subjected to impact in a direction endwise of the vehicle, the ends of the strips 6 will flex and yieldingly resist the impact by absorbing the shocks, and the 35 units may also flex to some extent. The portion of the units between the clamps 3 will usually be of double thickness, due to the overrunning of the ends of the units, and thus will provide a greater resistance to impact in the intermediate portion of the bumper. The supporting strip 6, by curving away from the unit to which it is attached and then toward it in the manner illustrated, will provide in a short length 40 a longer spring arm to be flexed than would be the case if the strip 6 merely extended directly or by simple curves from the clamp 3 to the support. This longer spring arm of the strip 6 increases its resiliency without materially decreasing its strength, and therefore the functioning of the bumper is greatly improved.

Referring to Figures 5 to 8, a pair of U-shape impact units 17 and 18 are arranged 55 in the same plane, and extend in opposite directions with the free ends of the arms abutting. The free ends of the arms are cut obliquely, as at 19, so that the abutting ends will overrun with one another to some extent. The ends of the arms of the impact units in the overrunning portions are provided with apertures 20, and a clamp plate 21, overlapping the abutting ends of both arms of the units, is provided with 60 dowel pins 22 which are adapted to enter the aper-

tures 20 and couple the abutting ends of the units.

The abutting ends of the arms of the units are also provided with aligned semi-circular notches 23, and a bolt 24 is adapted to pass 70 through the clamp plate 21, through the aperture formed by the aligned notches 23, and through an auxiliary plate 25 fitting against the inner faces of the units and joining the pairs of spaced arms. The 75 clamp plate 21 is provided with lugs 26 along each side edge which extend rearwardly for a purpose to be explained hereinafter.

A supporting bar 27 formed of flat strip 80 spring metal extends between the lugs 26 and an offset portion of the auxiliary plate 25 behind the abutting units, being clamped between the front clamp plate 21 and the rear auxiliary plate 25 by the bolts 24. 85 The lugs 26 space the bar 27 from the units and provide abutments against which the bar may be firmly clamped. The supporting member extends on each side of the clamp plate 21 and then curves transversely 90 thereto for attachment to bracket members 10, which may be carried upon the side bars 8 of the chassis frame.

Additional supporting members 28 are attached by bolts or rivets 29 to the cross arm 95 portions of the U-shaped impact units which are at the outer ends of the bumper, and then curve transversely to the impact units and along the ends of the supporting member 27 for attachment to the bracket member 100 10. The ends of the supporting member 27 which are attached to the bracket members 10, are preferably bowed in the direction of the length of the impact units so as to increase the resiliency of the bumper with- 105 out materially lessening its strength.

The U-shape impact units may be stamped from stock sheet material, such as sheet spring metal, or flat metallic spring bars may be twisted in their own plane, the ends 110 of the strips when being severed from the stock material being cut obliquely as illustrated, in order to obtain the overrunning of the abutting ends of the units. The supporting member 27 reinforces the impact 115 units at their junction, and since this junction is preferably at the central portion of the bumper, the central portion will be reinforced by the supporting member.

Referring to Figures 9 to 11, the U-shape 120 impact units 30 are supported at points adjacent their ends by curved resilient supporting strips or members 31, which are attached to the bracket members 10 and carry bolts 32 at their outer ends which pass through the slot or space between the arms of the U-shape units. The bolts 32 preferably have a large head 33 overlying the parallel arms of each unit, and have a shoulder 34, which is adapted to fit the space between 130

the arms of each unit and slide therealong when the curved strips are adjusted toward or from one another in fitting vehicles having different widths or distances between the 5 offset side bars 8 of the chassis frame.

The space between the arms of the impact units serves as a slot permitting the adjustment of the curved supporting strips 31 to different distances apart in adapting the 10 bumper to different vehicles. After adjustment has been made and the bumper is attached to a vehicle, the bolts 32 will be tightened so as to form permanent or tight connections between the impact units and 15 the supporting strips. The impact units may overrun and be joined in the manner illustrated in Figures 1 to 4, or in the manner illustrated in Figures 5 to 8. If desired the impact element may be stamped from a 20 single piece of sheet metal in the form of an elongated O with the supporting strips 31 attached to the ends of this element, through the slots by means of the bolts 32.

It will be obvious that various changes in 25 the details and arrangements of parts herein described and illustrated for the purpose of explaining the nature of the invention may be made by those skilled in the art within the principle and scope of the invention as expressed in the appended claims.

Claims:

1. A bumper for vehicles comprising a pair of U-shaped impact units extending in opposite directions and having the arms of 35 each overrunning those of the other, means for securing the units against separation from one another, and means for attaching the combined units to a vehicle, including a spring bar connected intermediate of its 40 ends to the combined units and at its ends to the vehicle whereby the impact units will be supported transversely of the vehicle.

2. A bumper for vehicles comprising a pair of U-shaped impact units extending in 45 opposite directions and having the arms of each overrunning those of the other, means for securing the units against separation from one another and a pair of spring bars each connected at an intermediate point to 50 the base portion of one of the units, extending along the unit for a distance, and then curved transversely of the unit for connection to a side bar of the vehicle frame.

3. A bumper for vehicles comprising a 55 pair of U-shaped impact units extending in opposite directions and having the arms of each overrunning those of the other, means

for securing the units against separation from one another, the base portion of each unit being curved backwardly upon itself 60 and spaced from its arms, and a pair of spring bars, each connected at an intermediate point to the curved back base portion of one of the units, extending along both the curved back and main portion of the 65 unit, and having its ends curved to extend transversely of the unit for connection to a side bar of the vehicle frame.

4. A bumper for vehicles comprising a pair of U-shaped impact units extending in 70 opposite directions and having the arms of each overrunning those of the other, means for securing the units against separation from one another, the base portion of each unit being curved backwardly upon itself 75 and spaced from its arms, and a pair of spring bars, each connected at an intermediate point to the curved back base portion of one of the units, extending along both the curved back and main portion of the 80 unit, and having its ends curved to extend transversely of the unit for connection to a side bar of the vehicle frame, said means for securing the units against separation also securing the portions of the spring bars 85 that extend along the main portions of the units to those units.

5. A bumper for vehicles comprising an impact element, and a pair of supporting strips of resilient material secured at points 90 intermediate their lengths to the opposite end portions of the element, each strip having one end turned transversely to the element for connections to a vehicle frame, the other end of each strip extending 95 along the element beyond the part of the vehicle to which it is to be attached, then transversely to the element, and then back toward the element to provide a portion for attachment to the vehicle frame. 100

6. A bumper for vehicles comprising a pair of U-shaped impact units having the ends of the arms cut oblique to the lengths of the arms, said units extending in opposite 105 directions in substantially the same vertical plane, and aligned with one another with the ends of the arms of each unit abutting and overrunning those of the other unit, means for coupling the abutting ends of the units, and means for supporting the 110 units from a vehicle frame.

In witness whereof I hereunto subscribe my signature.

SAMUEL H. SHAW.
